CLAIM

The ornamental design for a comb, as shown and described.

DESCRIPTION

FIG. 1 is a top, front, right side perspective view of a comb, showing our new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the comb in pressed state; and,

FIG. 10 is an enlarged view of portion 10 in FIG. 2.

The evenly dashed broken lines illustrate portions of the comb and form no part of the claimed design. The unevenly dashed broken lines define the boundaries of enlarged views and form no part of the claimed design.
